US0D1099533S

(12) **United States Design Patent** (10) **Patent No.:** **US D1,099,533 S**
(45) **Date of Patent:** **** Oct. 28, 2025**

(54) **DUFFEL BAG**

(71) Applicant: **YETI Coolers, LLC**, Austin, TX (US)

(72) Inventors: **Roy Joseph Seiders**, Austin, TX (US);
Erik Steven Larson, Austin, TX (US);
Derek G. Sullivan, Austin, TX (US);
Alex Baires, Austin, TX (US); **Jeffrey Charles Munie**, Austin, TX (US)

(73) Assignee: **YETI Coolers, LLC**, Austin, TX (US)

(**) Term: **15 Years**

(21) Appl. No.: **29/899,968**

(22) Filed: **Aug. 15, 2023**

Related U.S. Application Data

(63) Continuation of application No. 29/858,430, filed on Oct. 31, 2022, now Pat. No. Des. 1,016,492, which is a continuation of application No. 29/747,980, filed on Aug. 26, 2020, now Pat. No. Des. 968,088, which is a continuation of application No. 29/695,005, filed on Jun. 14, 2019, now Pat. No. Des. 896,516, which is a continuation of application No. 29/639,767, filed on Mar. 8, 2018, now Pat. No. Des. 851,400.

(57) **CLAIM**

The ornamental design for a duffel bag as shown and described.

DESCRIPTION

FIG. 1 is a top, front, right perspective view of a duffel bag showing our new design;

FIG. 2 is a front view thereof;

FIG. 3 is a rear view thereof;

FIG. 4 is a right side view thereof;

FIG. 5 is a left side view thereof; and,

FIG. 6 is a bottom view thereof.

The broken lines form no part of the claimed design. The vertical dashed lines represent unclaimed subject matter and form no part of the claimed design.

1 Claim, 5 Drawing Sheets
